GARMENT HANGER

William F. Helwig, West Allis, Wis.

Application January 23, 1946, Serial No. 642,913

1 Claim. (Cl. 223—96)

1

This invention relates to garment hangers and more particularly improvements on trouser hangers.

One of the objects of this invention resides in the provision of a trouser hanger adapted to grip the cuff portion of trousers and thereby retain the same in creased condition.

Another object of this invention resides in the provision of a trouser hanger adapted to grip the lower portion of the trousers under the influence 10 of a spring.

A further object of this invention resides in the particular construction of the body portion of the trouser hanger.

A still further object of this invention resides in the particular construction of the spring and hook supporting the body portion of the trouser hanger.

Aside from the aforesaid objects one of the salient features of this invention resides in the particular construction of the trouser engaging arms.

Among the many objects of this invention is the particular manner of assembling the jaws and spring within the body portion of the trouser hanger.

With these and other objects in view, this invention resides in certain novel features of construction and arrangements of elements to be hereinafter more particularly set forth in the specification, illustrated in the accompanying drawings and pointed out in the appended claim and, while this disclosure depicts my present conception of the invention, the right is reserved to resort to such changes in construction and assemblage of elements as come within the spirit of the invention.

In the accompanying drawings forming a part of this application;

Fig. 1 is a side view of the preferred form of this invention.

Fig. 2 is an end view thereof.

Fig. 3 is a sectional view taken approximately on line 3—3 of Fig. 2.

Fig. 4 is an enlarged sectional view through the pivoted portion of the hanger.

Fig. 5 is a detail perspective view of the spring and hook.

Fig. 6 is a perspective view of the cup shaped spacer engaged by the coils of the spring.

In the present illustration of this invention the numeral 5 designates, in general, a trouser hanger consisting of substantially U-shape members 6 and 7 disposed in opposed relation and connected together by a pivotal pin 8 beyond which are arms 9 formed on the body portion and carrying elongated jaws 10 having felt padding 11 or other suitable material secured to their inner surfaces, said arms preferably being of arcuate configuration to provide a minimum area of contact against the trouser cuff or adjacent portion thereof.

2

Disposed between the pivoted portions of the body members 6 and 7, is a cup shape spacer 12 around which coils 13 of a coil spring 14 are disposed. Said coil spring has its free end 15 bearing against the back wall of the member 6 and its opposite end 16 bearing against the back wall of the member 7 with its upper portion 17 directed centrally of said member 7 and passing through an aperture 18 in said member 7 beyond which the portion 16 of said spring is bent to form a hook 19 by which the hanger is removably supported from a bar or other suitable support generally employed for such purpose.

In order to strengthen the jaws 10, ribs 20 are stamped outwardly therefrom, the same also acting to prevent shifting or buckling of the felt padding.

With this invention fully set forth it is manifest that a trouser hanger of novel construction is provided and through the instrumentality of the cooperative assemblage of elements, positive gripping of the trouser legs or cuffs is assured with the possibility of the jaws leaving unsightly depressions obviated.

Having thus described my invention what I claim and desire to protect by Letters Patent is:

A trouser hanger comprising, opposed substantially U-shape body members having inturned upper ends of different lengths, a spacer between 30 certain portions of the body members, a pivotal pin passing through aligned apertures in the body members and spacer and retaining the same together, substantially U-shape arms formed on the body members below the pivotal pin thereof, 35 jaws secured to the lower ends of said arms in opposed relation to one another, padding secured to the inner opposed surfaces of the jaws, a coil spring having its convolutions loosely surrounding the periphery of the spacer with one end 40 thereof extending through a hole in the longer inturned end of the adjacent body member and its opposed end bearing against the inner surface of the other body member, and a hook formed on the outer end of that end of the coil 45 spring extending through the aforesaid hole in the inturned end of the body member.

WILLIAM F. HELWIG.
